United States Patent Office

Des. 227,051
Patented June 5, 1973

227,051

DISPLAY STAND FOR PICTURES OR THE LIKE

Jeffrey Snyder, New York, N.Y., assignor to Etna
Products Co., Inc., New York, N.Y.

Filed Mar. 8, 1971, Ser. No. 122,272

Term of patent 14 years

Int. Cl. D6—06, 07

U.S. Cl. D6—20

Fig. 1

Fig. 2

Fig. 3

Fig. 4

FIG. 1 is a front perspective view of a display stand for pictures or the like showing my new design;
FIG. 2 is a top plan view thereof;

FIG. 3 is a rear elevational view thereof; and

FIG. 4 is a bottom plan view thereof.

I claim:

The ornamental design for a display stand for pictures or the like, substantially as shown.
